DESIGN FOR A DRESS

Pauline Fracchia, New York, N. Y.

Application October 6, 1941, Serial No. 103,649

Term of patent 3½ years

To all whom it may concern:

Be it known that I, Pauline Fracchia, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view of Fig. 1, and

Fig. 3 is an enlarged fragmentary view of the dress shown in Fig. 1.

I claim:

The ornamental design for a dress, substantially as shown.

PAULINE FRACCHIA.
